Primary Examiner — Melody N Brown(74) *Attorney, Agent, or Firm* — Global IP Counselors, LLP(57) **CLAIM**

The ornamental design for a steering wheel for an automobile, as shown and described.

DESCRIPTION

FIG. 1 is a front elevational view of a steering wheel for an automobile showing our new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front perspective view thereof; and,

FIG. 8 is a rear perspective view thereof.

The mounting surfaces of the steering wheel, shown in broken lines in FIGS. 2 to 7, form no part of the claimed design since the inside surfaces are hidden when the steering wheel is mounted to the automobile.
